UNITED STATES PATENT OFFICE.

HOMER G. BISHOP, OF OAKLAND, CALIFORNIA, ASSIGNOR TO AMERICAN AUTOMATIC LOCK & LIFT COMPANY, OF SAN FRANCISCO, CALIFORNIA, A CORPORATION OF CALIFORNIA.

BED-MOUNTING.

1,384,008.

Specification of Letters Patent. Patented July 5, 1921.

Application filed February 15, 1918. Serial No. 217,388.

To all whom it may concern:

Be it known that I, HOMER G. BISHOP, a citizen of the United States, residing at 1450 35th avenue, Oakland, in the county of Alameda and State of California, have invented new and useful Improvements in Bed-Mountings, of which the following is a description.

My invention relates to the mounting of a bed so that it may be moved into or out of a receptacle; and more particularly to that form known as folding beds.

It has for one of its objects the arrangement of the bed mountings such that a minimum space is required in the wall or closet, within which the bed is to be located when not in use, and with the parts so arranged that the bed may be readily swung through an opening of minimum width to and from said receptacle and the room where it is to be used.

It also has among other objects the suspension of the weight of the bed and its mountings from a point above the floor, 25 preferably at or near the top of the opening of the wall, receptacle or closet, and doing away with the supporting instrumentalities heretofore usually forming a part of a bed mounting on or about the floor or wall side, 30 or within the aforesaid receptacle.

By referring to the attached drawings, my invention will be made plain.

Figure 1, shows the bed in its position of use in the room, in plan view.

Fig. 2, shows, in side elevation, the folded bed located within its receptacle and with the suspension structure.

Fig. 3 is a detail showing a plan of the lower linkage with other parts removed.

Fig. 4, shows the same parts when the bed is opened into the room.

Fig. 5, shows, in plan, the method of supporting the track.

Fig. 6, shows, in side elevation, an alternate method of supporting the track.

In Fig. 7, the rollers are shown on the supporting track as being flanged to retain their tracking alinement, whereas in Fig. 8 the rollers are shown without flanges, but 50 tracked between the two flanges of an eye beam, the flanges of said beam retaining the roller alinement.

Fig. 9, shows in elevation the top of the upright column with lever and link arrange-

ment and method of hanging from support- 55 ing track.

Throughout the figures similar letters refer to similar parts. *a* is the bed in its position of use within the room *b*. *c* is a closet or receptacle or space within the wall 60 within which the bed is adapted to be located when not in use. *d* is the body of the bed folding upward against the head structure *e*. *f* is the foot support which I prefer to fold down upon the bedding in the position shown in Fig. 2, when the bed is up-ended, and which retains the bed clothes and mattress tight against the body *d* when so up-ended.

The body *d* is adapted to swing about a 70 hinge *g* supported from the head member *e* and the vertical spindle *h*.

The vertical spindle *h* is suspended from the horizontal member *i* by a bearing, preferably of the well known ball bearing type, 75 *j*, so that it is free to swing about a vertical axis. The member *i* is adapted to travel horizontally with respect to the supporting member *k*, by the top roller *l* and under roller *m*.

I prefer to locate a track *o* on the floor, within the groove part of which, a pin or projection of the vertical spindle *h* may travel, thus confining it against side swinging during the travel of the bed through 85 the wall opening *n*, and while in its final position (shown in Fig. 1.)

I also prefer to mount upon said vertical spindle, projecting arms *p*, *p'*, with which arms are pivoted links *q*, *q'*. The opposite 90 ends of the links of *q*, *q'* are held by the fixed pivots *r*, *r'*, so that if the bed is rotated as shown by the dotted line in Fig. 1, from its position within the receptacle to its position in the room, the arms *p*, *p'* are rotated from the position shown in Fig. 3 to the position shown in Fig. 4.

I prefer to mount upon the said links *q*, *q'*, the pins *s*, *s'*, which when the bed occupies the position of Fig. 4, lock against the 100 arms *p*, *p'*, so that the bed cannot be pushed back into the closet without upending and giving it a rotary movement.

When the bed is rotated from its position of Fig. 3 to the position of Fig. 4, the stop 105 pins *s* and *s'* are finally brought against the sides of the levers *p* and *p'* thus locking the bed against further turning movement.

This is because the pivot t' has passed a straight line between the center of h , r' . It will be obvious to one skilled in the art that it is not necessary to locate the pivots r , r' upon the back wall of the receptacle, nor is it necessary to extend the supporting member k any greater length into the receptacle than required for the travel of the rollers l and m . This supporting member k may 10 be supported in any of a number of different ways so long as sufficient trackage is allowed. An alternate method is shown in Figs. 5 and 6, of supporting said supporting member.

15 The operation will be as follows: Assuming the bed to be "put up" within the closet, it is then brought into use by first rotating it about the vertical spindle (h) which rotation will cause the levers and links, (p) and (q) to force the said vertical spindle transversely through the closet to the position within the room. During this movement the bearing (j) on the member (i) advances while suspended by the rollers l and (m). The bed may now be let 25 down to its final position shown in full lines in Fig. 1.

The bed may be placed in storage by a reversal of the above operation—that is, it is 30 first upended and then rotated back into

the closet; the rotation of the vertical spindle through the lever (p) and link (q) causes the suspension bearing (j) and member (i) to be forced back into the closet through the rotation of rollers (l) and (m) 35 until it is in its complete inclosed position.

It is to be understood that after upending the bed of Fig. 1 it is to be pushed on one side toward the closet which will start rotation about h and the travel of h in the 40 track o under the control of links q and q' and such pushing and turning is continued until the final closet position of Figs. 2 and 3 is attained.

Having thus described my invention, I 45 claim:

A folding bed having a head structure wider when upended for concealment than the opening through which it is passed, a partially rotatable vertical member suspended from a horizontally slid able member, means supporting said slid able member from the ceiling and a plurality of devices compelling the coincident rotation and horizontal movement of the bed. 50

HOMER G. BISHOP.
